(57) CLAIM

I claim the ornamental design for a wreath, as shown.

DESCRIPTION

FIG. 1 is a top plan view of my wreath.

FIG. 2 is a front elevational view of my wreath.

FIG. 3 is a right side elevational view of my wreath; and,
FIG. 4 is a rear elevational view of my wreath.

The entire front and sides of my wreath is made of wine
bottle corks.
